DESIGN FOR CARPET.

No. 37,912.

Specification for Design.

Patented March 20, 1906.

Application filed January 8, 1906. Serial No. 295,188. Term of patent 7 years.

To all whom it may concern:

Be it known that I, JOHN S. McNAB, a citizen of the United States, and a resident of New York, county of New York, and State of New York, have invented a new, original, and ornamental Design for a Carpet, of which the following is a specification.

The figure of my new and original design, as shown in the accompanying drawing, and which I designate as No. 9,738, illustrates a section of a carpet having said design thereon.

I claim—

The ornamental design for a carpet substantially as shown.
